UNITED STATES PATENT OFFICE.

ALESSANDRO MICHETTI, OF ROME, ITALY.

DEVICE ADAPTED TO MAINTAIN FOR A PREDETERMINED PERIOD OF TIME A CONTINUOUSLY-MOVING BAND, FILM, OR THE LIKE OPPOSITE A STATIONARY BODY.

Application filed March 1, 1924. Serial No. 696,371.

To all whom it may concern:

Be it known that I, ALESSANDRO MICHETTI, a subject of the King of Italy, and residing at 3 Lungotevere Castello, Rome,

5 Italy, have invented certain new and useful improvements in devices adapted to maintain for a predetermined period of time a continuously-moving band, film, or the like opposite a stationary body, of which the

10 following is a specification.

The object of the invention is to provide a device adapted to maintain for a required period of time a length of a continuously moving band, film or the like stationary opposite a stationary body. This device is intended more particularly for use in cinematographic apparatus, but it may of course be applied to any other use where the same purpose is to be obtained.

20 Supposing the invention be applied to a cinematographic apparatus where a length of film must be held stationary opposite the lens for a suitable period of time to produce its impression and after the impression be rapidly removed and replaced by a fresh length of film.

According to the invention this is not obtained by imparting an intermittent motion to the film as usual, but the film is 30 made to travel with a continuous forward motion and the length of the film to be impressed is held opposite the lens for the period of time required for its impression by the said length of film being displaced 35 in an opposite direction to the travel of the film and with a speed equal to the speed of travel so that the film is held as it were stationary before the lens. After the impression the auxiliary motion is inverted 40 and the speed of this motion almost instantaneously increased so that the length of film that has been impressed is rapidly carried out of the reach of the lens not only through the reversed auxiliary motion but 45 also through the forward travel of the film. These two motions will be adjusted so that their combined effect will be to displace the film exactly to the extent of the impressed length of film.

50 The auxiliary motion of the film first in an opposite direction to its travel and thereafter in the direction of travel may be obtained in many ways, for example by mounting the sprocket wheel that feeds the 55 film on a slidable support adapted to have

a vertical to and fro motion imparted to it by a cam acting on the support and controlled by the driving mechanism of the apparatus.

The drawing shows schematically by way 60 of example a constructional form of a device according to the invention, Figure 1 being a side view and Figure 2 a front view thereof.

The film travels with a continuous motion in the direction indicated by the arrows from stationary rollers 2, 2' to stationary rollers 3, 3' by way of rollers 4, 5, 6 mounted on a slidable support 7. The rollers 4 and 6 are loosely mounted on their 70 axles, while the roller 5 which is provided with teeth to engage the usual perforations in the film, has a continuous and uniform rotary motion imparted to it to produce the advance of the film.

75 The toothed roller or sprocket wheel 5 receives its rotary motion through a pivotally mounted lever 8 from a gear wheel 9 which meshes with a gear wheel 10 on a driving shaft 11.

80 The slidable support 7 has mounted on its lower end a notched member 12 adapted to receive between its jaws the circumferential flange of a cam 13 so as to have to follow the contour of the cam during its 85 rotation. The cam is secured to a flywheel 14 which is rigidly connected with the gear wheel 10 and with the shaft 11 which by means of a motor or a crank handle and a suitable gearing has a rotary motion im- 90 parted to it to drive the mechanism.

In the example illustrated the gear wheel 9 is supposed to make one revolution for each three revolutions of the gear wheel 10 and the sprocket wheel 5 will thus have 95 completed one third of its revolution when the gear wheel 10 has completed one revolution and this allows the circumference of the wheel 5 being equal to the length of three photographs.

100 The cam 13 is shaped so as to produce during five sixths of its revolution, viz, between the points 16 and 15, a uniform upward movement of the slidable support with a speed equal to that imparted to the 105 film in the opposite direction by the sprocket wheel 5. In this way, a point, for example 17, will be caused to remain stationary before the lens of the cinematographic apparatus. During the remaining part of its 110

revolution, viz, between the points 15 and 16, the cam will produce a rapid backward movement of the slidable support 7, which assists the continuous forward travel of the film, so that the impressed length of film will be rapidly removed and replaced by a new length of film. The support is then again caused to rise by the cam so as to allow this new length of film being impressed.

The film 1 is guided between the rollers 2, 2' and the roller 4 by a guide 18 and between the sprocket wheel 5 and the rollers 3, 3' by a guide 19, these guides being suitably hinged so as not to interfere with the to and fro motion of the support 7, the latter being guided in any convenient way to secure a perfect vertical sliding motion.

The film is introduced between the rollers 2, 2' and will be engaged by the sprocket wheel 5 so that on the mechanism being turned the film is caused to travel along the guide 19 and through the rollers 3, 3' out of the apparatus.

What I claim is:

1. A cinematographic film feed device, comprising, oscillable parallel film guide arms, a reciprocable frame pivotally mounted on the guide arms, means for reciprocating

ing the frame, and a sprocket film drive 30 roller carried by the said frame, said means for reciprocating the frame including, a rotatable disk, a cam on the disk and projecting at substantially right angles to the face of the disk, and a forked shape arm connected to the frame, the forked shape arm engaging the cam on either side thereof.

2. A cinematographic film feed device, comprising, oscillable parallel film guide arms, a reciprocable frame pivotally mounted on the guide arms, means for reciprocating the frame, and a sprocket film drive 40 roller carried by the said frame, said means for reciprocating the frame including, a rotatable disk, a cam on the disk and projecting at substantially right angles to the face of the disk, and a forked shape arm connected to the frame, the forked shape arm engaging the cam on either side thereof, the forked shape arm and the frame being rigidly interconnected, all the parts of the fork being stationary, whereby to avoid lost motion.

In testimony whereof I have signed my name at Rome this 12th day of January, 55 1924.

ALESSANDRO MICHETTI.
